CAN OPENER

Filed Nov. 26, 1927

UNITED STATES PATENT OFFICE

HENRY W. OTTOW, OF WATERTOWN, SOUTH DAKOTA

CAN OPENER

Application filed November 26, 1927. Serial No. 235,944.

This invention relates to can openers, and the general object of the invention is to provide a can opener which is particularly effective in actual practice, which is so formed that it cannot slip from the can once the knife or blade has been inserted in the can top; which is provided with a toothed rocking face or fulcrum which will indent the bead of the can top, and which will prevent any backward slip of the opener when being used.

A further object is to provide a blade which will bead, crimp or turn over the raw edge of the can upon the inside face thereof as the top is cut from the can so that the contents of the can be poured without catching on the edge and so that the empty can may be used for other purposes.

Other objects will appear in the course 20 of the following description.

My invention is illustrated in the accompanying drawing, wherein:—

Figure 1 is a side elevation of a can opener constructed in accordance with my invention;

Figure 2 is a rear edge elevation thereof;

Figure 3 is a side elevation looking from the side opposite to that shown in Figure 1;

Figure 4 is a fragmentary elevation as in Figure 1, showing the can opener applied;

Figure 5 is a side elevation of the shank.

Referring to the drawing, 10 designates the handle of the can opener and 11 the shank of the opener proper which is formed with a longitudinally extending tang 12 engaging within the handle in the usual manner. This shank is formed with the curved bottle opening hook 13. The shank on the side edge opposite the hook 13 is formed with an inclined portion having teeth 14, these teeth being triangular in shape and pointed so as to engage against the bead of the can, as will be stated later.

The blank from which the shank is made is formed with a guard 15. This guard extends downwardly and laterally, or in other words at an inclination away from the hook 13, and in actual practice this guard is bent over or twisted so that it lies in a plane at right angles to the plane of the shank 11

and at an angle to the axis of the tang 12. Welded, riveted or otherwise attached to the shank 11 on that face of the shank away from the twisted guard 15 is a blade 16, this blade being formed with a shank portion which lies flat against the shank 11 and with a cutting portion provided with a straight cutting edge 17 and a curved cutting edge 18, the straight cutting edge being disposed in line with the adjacent edge of the shank 11 and parallel with the axis of the tang 12. When the blade is so disposed and welded in place, the end of the blade projects beyond the guard 15, as shown in Figure 1, with the straight edge of the blade disposed in line with the adjacent edge of the shank and the curved edge of the blade projecting beyond the guard.

Looking toward the edge of the implement, as shown in Figure 2, it will be seen that the inner edge of the guard is spaced from the blade. It will also be seen from this view that the extremity of the blade is slightly curved at 19, this curvature being away from the guard. The shank 11 with the parts 12, 13, 14 and 15 is made of cold rolled strip steel about $\frac{3}{16}$ " thick and is case hardened. The blade is preferably made of tool steel, oil tempered and drawn to a medium hardness. The blade is beveled on both edges and a slight bend given to the end of the blade to permit the blade to cut freely around the edge of the can. Preferably the blade will be spot riveted or welded on the shank 11.

In the use of this device, the hook 13 may, of course, be used for the purpose of a bottle cap remover. This requires no further explanation. Where the implement is to be used for opening cans, the blade is forced into the top of the can adjacent the edge thereof, so closely adjacent that the inner edge of the guard will slip over the exterior wall of the can, thus bringing the bead of the can between the guard and the blade. The blade is forced into the can sufficiently deeply so that the "creeper" formed by the teeth 14 will engage this bead. When the blade has been thus forced inward, the handle is forced downward, causing the implement to rock upon the teeth 14 as upon a fulcrum and lift-

ing the forward curved edge of the blade. This curved edge will cut into the material of the can. When one cut is made, the blade is forced forward and downward and a new cut made. Thus by merely rocking the implement upon the can, the blade will be caused to cut the can entirely around closely adjacent the outer wall of the can, the guard preventing any inward movement of the blade. The blade as it rocks forces the cut edge of the can top which is adjacent to the wall to the can downward against the wall of the can and smoothes this edge off so that there is no projecting cutting edge upon the can itself when the top has been cut out. Thus the contents of the can can be poured without catching on the edge of the can and the empty can may be utilized for a drinking cup, flower pot and various other purposes. The toothed rocker 14 is particularly effective, as this prevents the knife from slipping back as the handle is forced downward and the knife is forced upward into the can. Thus there is no lost motion with this can opener. As before remarked, the blade is slightly bent at the point so that it will cut freely around the edge of the can and not bear frictionally against the wall of the can. Minor changes, of course, may be made in the details of construction and arrangement of parts without departing from the spirit of the invention as defined in the appended claim.

I claim:-

A can opener comprising a shank having a handle, the shank having attached thereto a longitudinally extending blade having a straight edge and a curved intersecting edge, the straight edge being parallel to the longitudinal axis of the shank; the shank being formed with a straight guard extending diagonally across the blade from a point opposite the base of the curved edge to a point approximating the forward end of the straight edge and disposed in a plane at right angles to the plane of the shank, the inner edge of the guard being uniformly spaced from the blade throughout its entire extent the shank having a plurality of teeth constituting a fulcrum upon which the shank may rock when the blade is inserted in the can; said teeth being disposed in a series in angular relation to the guard.

In testimony whereof I hereunto affix my signature.

HENRY W. OTTOW.
